CLAIM

The ornamental design for a mattress cover assembly, as shown and described.

DESCRIPTION

FIG. 1 is a front elevational view of the mattress cover assembly of the present invention;

FIG. 2 is a rear elevational view of the mattress cover assembly of FIG. 1;

FIG. 3 is a left side elevational view of the mattress cover assembly of FIG. 1;

FIG. 4 is a right side elevational view of the mattress cover assembly of FIG. 1;

FIG. 5 is a top view of the mattress cover assembly of FIG. 1;

FIG. 6 is a bottom view of the mattress cover assembly of FIG. 1; and,

FIG. 7 is a perspective view of the mattress cover assembly of FIG. 1.

The broken lines in the drawings represent portions of the mattress cover assembly that form no part of the claimed design.
